HAND APPLICATOR FOR VARNISH, POLISH,
AND THE LIKEErnest R. Erickson, Des Moines, Iowa, assignor to
C. E. Erickson Company, Inc., Des Moines,
Iowa

Application July 23, 1934, Serial No. 736,571

4 Claims. (Cl. 15—231)

The object of my invention is to provide a hand applicator of very simple and inexpensive and durable construction, which can be used for applying varnish, polish, paint or the like rapidly and evenly.

A further object is to provide such a device so constructed that a short strip of carpet or the like having a thick nap can be easily and conveniently assembled on a handle or holder without the use of additional parts such as screws or bolts and will be firmly held in folded position for exposing the nap for the application of the varnish and so forth.

Still another purpose is to provide in combination with such a device a receptacle adapted to receive wax, varnish or the like and to be used also as a container for the applicator.

It is my purpose to provide such a container which is provided with a member adapted to serve as a handle when the device is used to contain wax or the like and to cooperate with the body of the container for holding the applicator therein, and which affords means for hanging the container with the applicator received therein on a wall.

With these and other objects in view, my invention consists in the construction, arrangement and combination of the various parts of my hand applicator, whereby the objects contemplated are attained, as hereinafter more fully set forth, pointed out in my claims, and illustrated in the accompanying drawing, in which:

Figure 1 is a perspective view of my device for applying wax, varnish, paint or the like.

Figure 2 is a plan view of the strip which is used in cooperation with the handle member for holding the carpet or the like.

Figure 3 is a plan view of the container with the assembled applicator therein and the container handle closed.

Figure 4 is a sectional view taken on the line 4—4 of Figure 3; and

Figure 5 is a vertical, sectional view of the container with the handle raised, taken on the same section line.

My improved applicator includes a handle A, a toothed strip B and a container C.

The handle A is preferably made from a single strip or sheet of somewhat resilient metal. The strip is folded at the center to form the larger part of a cylinder 10. From the sectional cylinder 10, the lengths of the strip extend away from the portion 10 in parallel portions 11.

At the ends of the portions 11 farthest from the sectional cylinder 10, the strip lengths are ex-

tended oppositely away from each other to form the flanges or shoulders 12. From the flanges or shoulders 12 the strip lengths extend away from the sectional cylinder in parallel portions 13, which terminate in inwardly extending flanges 14, which extend toward each other, and are normally slightly spaced apart at their closest edges.

Thus it will be seen that the handle A comprises a single sheet of metal bent to form a portion of a hollow cylinder with parallel portions 11 extending therefrom and terminating in two oppositely facing channel members, each composed of a flange 12, portion 13 and a flange 14.

This handle A is assembled with a strip of carpet or the like 15 having a deep nap. The carpet 15 or the like is folded over so that the ends are parallel and close together, and are slipped between the channel-shaped members above described.

For cooperation with the handle proper and the carpet strip 15, I provide a toothed metal strip B, shown in Figure 2.

The strip B is provided with two rows of projecting teeth 16, the rows being parallel with each other and being indicated at D and E.

The respective teeth of the row D are substantially aligned with the respective teeth of the row E, transversely of the strip B. The teeth are formed by cutting V-shaped slits in the strip B, and then bending the teeth away from the strips.

The transversely opposite teeth of the respective rows are bent away from the strip on the same side. Thus the right-hand tooth of the row D and the right-hand tooth of the row E are bent from the strip and away from the observer. On the other hand, the next tooth to the left in the row D and the next tooth to the left in the row E are bent away from the strip and toward the observer. This arrangement is continued to the left-hand end of the strip B.

In assembling the carpet strip 15 on the handle A, the strip of carpet is bent double, as shown for instance in the drawing, with the toothed metal strip B between the free ends of the strip 15 and adjacent the edges thereof parallel with such edges.

The ends of the strip 15 holding between them the toothed metal strip B are then slipped endwise between the portions 13 and the flanges 14 of the handle A. Care is taken to see that the flanges 14 are between the rows of teeth D and E, as illustrated for example in Figure 4.

The parts are so arranged that the flanges 14 are resiliently pressed into the nap for pressing the ends of the carpet toward the opposite sides

of the body of the strip B and between the respective rows of teeth D and E. This mode of clipping the carpet strip is illustrated in Figure 4.

The device in its assembled form is illustrated in Figures 1, 3 and 4.

In Figures 3, 4 and 5, I have illustrated the container C, which is preferably used with my device. The container C comprises a pan, with the bottom 17, the upwardly inclined side and end walls 18, and pivoted handle 19. The container C is preferably pressed out of metal, although it may be made of other material. The lower edges are rounded as at 20 in Figure 5, and the corners are rounded as indicated at 21 in Figure 3. At the sides and ends, the walls 18 are provided with rolled edges 22 for convenience in handling, for reinforcement purposes, and to eliminate sharp edges. The rolled portions 22 are omitted at the corners for convenience in manufacturing.

There is a slot 23 cut in the rolled edge at the back of the container and at the middle thereof.

The handle 19 is composed of a strip of metal, having its intermediate portion provided with the reinforcing ribs 24. Near one end of the handle 25 and beyond the ribs 24, pintle tongues 25 project opposite laterally. They are formed integrally with the handle 19, and are preferably more or less rolled to form pintles received in the rolled edge 22 at the back of the container.

As illustrated in Figure 3, it will be observed that a portion of the handle 19 projects beyond the pintle members 25 and has a hole 26. The object of providing this projecting portion indicated at 19a is to afford a part that will engage the back wall of the container, when the handle is raised and moved slightly beyond vertical position for holding the handle in upright position, as shown in Figure 5, so that it can be conveniently grasped for moving the container from place to place.

At the opposite end of the handle 19, it is bent to form a catch member 27 adapted to snap over the rolled edge 22 at the front of the container and resiliently engage thereover for holding the handle in closed position as best shown in Figure 4.

The handle 19 is preferably slightly curved from end to end as illustrated also in Figure 4.

I shall now refer to the practical use of my device.

Assuming that the device is assembled as shown in Figure 1, it is then ready for use in applying wax, varnish, polish, paint or the like. If, for example, it is desired to varnish the top of a desk, the liquid varnish may be poured into the container C. The parts are of such relative sizes that the folded central portion of the carpet strip 15 may then be dipped into the container C and into the contents, such as varnish, thereof. The varnish can then be applied to the desk rapidly and evenly.

It is obvious that liquid wax, furniture polish, screen paint or the like can be similarly applied with my device.

In applying paint to screen wire, the device is properly operated, so as to give the carpet strip 15 a rotary motion.

It is very easy to remove the carpet strip and replace it with another if that is desired.

I have found that a device of this kind is substantially more economical in use than is a brush. It is more satisfactory in applying wax than is a brush, since it gives a smoother and more even

application of the wax and has a better polishing effect.

It can be used for more purposes than a brush. A brush, for instance, is not satisfactory in applying furniture polish.

It is much faster than a brush in many of the uses to which it can be put, especially for example in painting screens.

After the device has been used, the container and applicator are cleaned with turpentine or the like, and the applicator placed in the container as shown in Figures 3 and 4, the handle 19 snapped down to closed position as illustrated in Figure 4, and the container with the applicator therein, hung on a nail or the like 28.

It will be observed that there may be some modifications in the structure of the device, for instance the portions of the handle A, which form the jaws for receiving the ends of the carpet strip might be changed somewhat, and need not be integral with the portion 10, but I preferably make the device of a single strip of metal as shown.

While for purposes of illustration, I have shown and described a specific embodiment of my invention, it is obvious that modifications thereof are possible, and that my invention is not intended to be restricted, except insofar as necessitated by the prior art and the spirit of the claims.

I claim as my invention:

1. In a device of the kind described, a handle having resilient jaw members, provided with opposite flanges projecting toward each other, a toothed metal strip arranged between the jaw members, and having rows of teeth, the teeth of the respective rows being inclined alternately away from the body of the strip on opposite sides thereof for engaging material between the strip and the jaws.

2. In a device of the kind described, a handle having resilient jaw members, provided with opposite flanges projecting toward each other, a toothed metal strip having rows of teeth, the teeth of the respective rows being inclined alternately away from the body of the strip on opposite sides thereof for engaging material between the strip and the jaws.

3. In a device of the kind described, a handle formed of a single piece of resilient metal folded to form a handle portion with an enlarged part at one end and a pair of spaced jaw-like members at the other end, having inwardly extending flanges, a toothed metal strip interposed between the jaws having rows of teeth, the teeth of the respective rows being inclined alternately away from the body of the strip on opposite sides thereof.

4. In a device of the kind described, a handle having resilient jaw members provided with opposite flanges projecting toward each other, a toothed metal strip having projecting teeth, the strip being adapted for insertion between the jaws to be resiliently held for holding material adjacent the strip and between the jaws.
